UNITED STATES PATENT OFFICE.

CYRUS DOLPH, OF PRESTON, ONTARIO, CANADA.

COMBINATION DINING TABLE AND CABINET.

Application filed November 1, 1926. Serial No. 145 578.

This invention relates to the combination with a dining table of a cabinet or cabinets adapted to contain articles generally used in setting a table, and preferably provided also with electrical connections for attaching a toaster, percolator and the like.

The general object of the invention is to provide a device of this kind which is made preferably of metal, and is foldable in such a manner that it may pass through a doorway of ordinary size. It may, therefore, be furnished in the kitchen, the necessary articles for setting the table being placed in the cabinets, and swung underneath the table. It is then rolled into the dining room, where the contents of the cabinets are placed upon the table, or returned to the cabinets, as occasion may require. After the meal is finished, the table may be cleared, all the articles being placed in the cabinets, and the combination table and cabinet is again folded and returned to the kitchen.

The invention consists further in various details of construction and combinations of elements, the nature and purpose of which will be more fully explained in connection with the accompanying drawings, which illustrate one form in which the invention may be embodied.

30 In the drawings:

Figure 1 is a perspective view of the invention extended.

Figure 2 is a perspective view of the same folded.

35 Figure 3 is a plan view of the invention.

Figure 4 is a vertical section taken on the line 4—4 of Figure 3.

Figure 5 is a detail sectional view, showing the means for supporting the table leaves 40 in extended position.

Figure 6 is a detail sectional view, illustrating the means for supporting one of the cabinets.

45 Figure 7 is a detail sectional view taken on the line 7—7 of Figure 6.

As shown in the drawings, the table top 1 is preferably made from metal, with a peripheral downturned flange 2. The table top is supported by legs 3 in the shape of angle bars, and each leg is secured by a bracket 4 to the flange 2, and is provided at its lower end with a castor 5.

A cabinet 6 is supported on each leg 3 by means of brackets 7 and 8, and is adapted to 55 be swung underneath the table, as shown in

Figure 2, or to be swung outwardly to the position shown in Figure 1. The upper bracket 7 has arms 9 secured to the sides of the cabinet, and a sleeve 10 journaled on a bearing 11 secured to the table leg. The bracket 8 is secured to the bottom of the cabinet, and is formed with a sleeve 12 journaled on a bearing 13 secured to the table leg. For convenience in assembling the device, each bearing 11 and 13 is made in two sections, as shown in Figure 6, which are secured to the table leg by pins 14.

The table top 1 is provided on each side with an extension leaf 15 connected thereto by hinges 16, the separate parts of which may be stamped out of metal, forming the edges of the leaf and table top, respectively. When the cabinets 6 are swung outwardly and the leaves 15 are raised, each leaf is supported at each end by an arm 17, which is pivoted at 18 to the side of the cabinet, and is provided with a handle 19. The end of the arm 17, when swung upwardly, engages a channel shaped seat 20 secured in the outer corner of the table leaf.

Each cabinet 6 is rectangular in shape, and provided with separator bars 21 across the front forming ways for the drawers 22. The number and depth of the several drawers may be arranged as desired.

One or more of the cabinets 6 is preferably provided with an electric socket 23, which may be connected by a conductor 24 to any suitable outlet from the house current. The socket 23 is electrically connected to a 90 socket 25 to which may be connected a conductor 26, which is attached to any electric utensil 27, which it may be desired to use during the meal.

In using the combined dining table and cabinet, it is brought into the kitchen, and the articles to be used during the meal are placed in the cabinets 6, and the latter swung underneath the table, as shown in Figure 2. The table is of such a size that when the 100 cabinets are swung inwardly, and the leaves 15 lowered, the table may pass through an ordinary doorway. The legs are provided with castors 5, so that the table may be easily rolled from the kitchen to the dining room, 105 or vice versa. When the table has been moved to the dining room, the cabinets are swung outwardly, as shown in Figure 1, and the leaves 15 are raised and held in extended position by the arms 17. In this position, 110

the table may be set and the meal served. At the conclusion of the meal, all of the articles may be returned to the cabinets, and the table folded and returned to the kitchen.

5 As shown in Figure 3, the cabinets are of such size that they may all be swung underneath the table to the position shown in dotted lines.

Instead of using ordinary electric appliances to be placed upon the several cabinets 10 and suitable electrical connection made, as shown in the drawings, said appliances may be built into the structure, in an obvious manner, and be equipped with thermostatic controlling means, if desired.

While I have shown and described in detail the preferred construction of the invention, it is to be understood that it is not limited to the precise form shown, but that 20 modifications may be made in the size, shape and general arrangement of the various features without any material departure from the salient features of the invention as claimed.

25 What is claimed is:

1. The combination with a table including a top, legs supporting the top and extension leaves hinged to the side edges of the top, of a plurality of cabinets revolvably mounted on 30 the respective legs so as to swing inwardly underneath the table top or outwardly beyond the same, and means connected with the cabinets to support the adjacent ends of two table leaves in extended position when 35 the cabinets are in their outer positions.

2. The combination with a table including a top, legs supporting the top and extension leaves hinged to the top, of cabinets associated with the respective legs, each cabinet 40 having brackets secured thereto and each formed with a sleeve, said sleeves being in vertical alinement with each other, bearing members secured to each leg and having cylindrical surfaces on which the sleeves of 45 the corresponding cabinet brackets are ro-

tatably mounted, so that the cabinets may be swung inwardly underneath the table top or 180° outwardly beyond the same with their upper ends fully exposed, and means connected with the cabinets to support the 50 table leaves in extended position when the cabinets are in their outer uncovered positions.

3. The combination with a table including a top with legs supporting the same and extension leaves hinged to the top, of cabinets revolvably mounted on the respective legs so as to swing underneath the table top or outwardly beyond the same with their upper 55 ends fully exposed, each table leaf having a recess on the underface near each end, and members pivoted to the side faces of the cabinets and moveable into the respective recesses to support the leaves in extended 60 position after the cabinets have been swung into their outer positions, and to prevent the latter from swinging.

4. The combination with a table including a top with legs supporting the same, of cabinets associated with the respective legs, each cabinet having brackets secured thereto and each formed with a sleeve, said sleeves being in vertical alinement with each other, bearing members secured to each leg and having cylindrical surfaces on which the sleeves of 75 the corresponding cabinet brackets are rotatably mounted, so that the cabinets may be swung inwardly underneath the table top or outwardly beyond the same, each table leaf having a recessed member secured to the 80 underface thereof near each end, and arms pivoted to the side faces of the cabinets and movable into the respective recesses to support the table leaves in extended position after the cabinets have been swung into their 85 outer positions.

In testimony, that I claim the foregoing as my own I have hereto affixed my signature.

CYRUS DOLPH.
